UNITED STATES PATENT OFFICE.

GEORGE E. GRAY, OF COMPTON, CALIFORNIA, ASSIGNOR OF ONE-THIRD TO EDWARD A. CARSON, OF LOS ANGELES, CALIFORNIA.

CARBURETER.

1,275,150.

Specification of Letters Patent. Patented Aug. 6, 1918.

Application filed March 1, 1917. Serial No. 151,797.

To all whom it may concern:

Be it known that I, GEORGE E. GRAY, a citizen of the United States, residing at Compton, in the county of Los Angeles and

5 State of California, have invented new and useful Improvements in Carbureters, of which the following is a specification.

This invention relates to a carbureter and particularly pertains to an automatic valve 10 therefor.

It is an object of this invention to provide a carbureter with an air valve which will act automatically to control the inflow of air to the carbureter prior to its carburization with the liquid fuel.

Another object of this invention is to provide a valve which will automatically regulate the richness of the gaseous fuel produced within the carbureter and regulate 20 it in direct relation to the fuel requirements of the engine for which the new carbureter is provided.

Another object of this invention is to provide a manually operated throttle valve 25 adapted to accurately regulate the volume of gaseous fuel passing to the engine.

Another object of this invention is to provide mechanical means for mixing the gaseous fuel as it passes to the engine and 30 thereby insuring that it will be thoroughly carbureted.

It is a further object of this invention to provide a carbureter possessing the above named features which is formed of few operative parts and which is simple in construction and operation.

Other objects will appear hereinafter.

The invention is illustrated, by way of example, in the accompanying drawings, in 40 which:

Figure 1 is a view in side elevation illustrating the carbureter and particularly disclosing the carbureter chamber with parts broken away to more clearly set forth its 45 construction.

Fig. 2 is a view in side elevation illustrating the assembled carbureter and disclosing the disposition of the manually operated throttle valve in relation to the carbureter chamber and the automatically operating valve.

Fig. 3 is a view in side elevation illustrating the manually operated throttle valve as illustrated from its operative position 55 upon the carbureter.

Fig. 4 is a view in end elevation illustrating the mixer by which the gaseous fuel is agitated as it leaves the carbureter and enters the manifold of the engine.

Referring more particularly to the drawings, 10 indicates a carbureter having a float chamber 11 fitted with a suitable float and fuel valve control means to regulate the flow of liquid fuel into the carbureter from a fuel supply pipe 12. Leading from the float chamber is a fuel duct 13 which is regulated by a needle valve 14 and which communicates with a series of nozzles 15. These nozzles extend through an air inlet passage-way 16 and terminate upon the outer side 70 of a partition wall 17. This wall divides the air inlet passage-way from a carbureter chamber passage-way 18. The nozzles are upturned within this chamber and are adapted to permit air passing by them to absorb the liquid fuel passing from the float bowl. An opening 19 is formed above each of the nozzles and communicates with the air passage-way 16, thereby allowing the liquid and air to pass through an opening 80 20 in the bottom of the air chamber and against the manually operated valve 21. Attention is directed to the fact that it is desirable to use a series of the fuel nozzles and to dispose them in horizontal relation 85 to each other. In this position they are separated by partition walls 22 extending up to the valve 21, thus insuring that the liquid fuel will be thoroughly distributed throughout the volume of air passing 90 through the carbureter chamber 18 to the valve 21.

The valve 21 is cylindrical in shape and is disposed in a horizontal position within a case 23 formed integral with the carbureter 95 and air inlet passage-ways. An opening 24 is formed throughout the length of this valve. This opening is triangular in shape having its hypotenuse extending the length of the valve wall and parallel to the valve axis and having its base disposed at right-angles to said axis. In this manner the throat of the air inlet passage-way 16 may be gradually opened to permit one or more of the nozzle chambers 22 to communicate 100 with the interior of the valve and the engine. This valve is controlled by a throttle lever 25 suitably connected with operating means conveniently disposed in relation to the operator.

As a means for automatically controlling the volume of air passing to the valve 21 and the richness of fuel mixture generated within the carbureter chamber 18, a wing 5 valve 26 is provided. This valve is pivotally mounted for vertical movement upon a pin 27 formed on the center line of the partition wall 17 and disposed adjacent the lower end or mouth 28 of the air passage-way 16 and the carbureter chamber 18. The valve is formed with two wings, a long wing 29 which corresponds in width to the width of the air passage-way 16 and a short wing 30 corresponding in width to the width of 10 the carbureter passage-way 18. These wings are disposed at an angle to each other, the angle having been determined by the experiment and in consideration of the fuel capacity of the engine. The wing 29 is heavier 15 and longer and overbalances the wing 30, so that the carbureter chamber 18 leading past the discharge ends of the fuel nozzles is normally open, and the wing 29 presents a larger surface to the lifting force of the 20 sucking air and by this force overbalances the wing 30 the other way, tending to close the carbureter passage and open the air passage, thereby increasing the resistance through the carbureter chamber and reducing 25 the resistance in the passage-way 16.

In order to insure that the gaseous fuel produced within the carbureter is thoroughly mixed, an agitator 31 is mounted in the mouth of the valve casing 23 which 30 closes the manually operated valve. This member is provided with a series of inclined vanes 33 which impart a gyroscopic movement to the fuel mixture and act to 35 thoroughly break up the atoms of liquid fuel and cause it to be properly mixed with the air.

In operation, the engine upon which the carbureter is mounted is started by any desired means and will immediately create a 40 suction through the mouth 28 of the carbureter. This will cause the valve 26 to be lifted and its wings 29 and 30 to substantially stand in a counter-poised position.

Air will pass upwardly through the air inlet passage-way 16 and the carbureting chamber 18. The air passing through the carbureting chamber will gather liquid fuel as it rushes by the fuel nozzles 15 and will again unite with the air passing along the 50 passage-way 16. As it passes through the opening 20 its flow will be controlled by the movement of the valve member 21 which is rotated to open and close a given number of the compartments 22'. As the engine 55 accelerates, the wing 29 of the valve member 26 will gradually rise and cut off the passage-way through the carbureting chamber. This, it will be seen, produces a lean mixture. When the engine labors under a 60 heavy load, the suction will be decreased 65

and the valve wing 29 will fall as the wing 30 is raised, thereby increasing the richness of the fuel mixture when the throttle position is unchanged. It will be understood that even when the air intake passage to the carbureter chamber is entirely closed a certain amount of volatilization of the fuel will take place due to the partial vacuum within said chamber. Especial attention is called to the throttle valve 21, the mixture 70 passage 18, and the air passage 16 leading to the throttle valve and having vertical intakes 28, the nozzles 15 leading fuel into the mixture passage, and the air valve 26 freely mounted and having a short wing 30 75 extending into the mixture passage intake and a long wing 29 extending into the air passage intake, said wings being set so that when the air passage wing 29 is closed the mixture passage wing 30 is open, the air 80 passage wing being of larger area and heavier than the mixture passage wing, so that the mixture passage wing is normally open and is closed more or less as the suction against the air passage wing varies. 85

It will thus be seen that the carbureter here disclosed provides simple manually operating means for absolutely controlling the volume of gaseous fuel flowing to the engine cylinders and automatic means for 90 regulating the richness of the fuel in relation to the engine requirements.

While I have shown the preferred construction of my carbureter as now known to me, it will be understood that various 100 changes in the combination, construction and arrangement of parts may be made by those skilled in the art without departing from the spirit of my invention.

I claim:

1. In a carbureter, a throttle valve, means forming a mixture passage and an air passage side by side leading to the throttle valve and having vertical intakes, means for leading fuel into the mixture passage, and an air valve freely mounted with a wing extending into the mixture passage intake and a wing extending into the air passage intake, said wings being set so that when the air passage wing is closed the mixture passage wing is open, the air passage wing being of larger area and heavier than the mixture passage wing; so that the mixture passage wing is normally open and is closed more or less by suction against the 110 air passage wing.

2. A carbureter comprising fuel supply means, a series of horizontally disposed ducts leading from said supply means, means forming a mixture passage having an independent vertical passage-way into which each duct discharges, a throttle valve to which the mixture passage leads, means forming an air passage leading to the throttle valve, said mixture passage and said air 120 125 130

passage having vertical intakes side by side, and an air valve freely mounted with a wing extending into the mixture passage intake and a wing extending into the air 5 passage intake, said wings being set so that when the air passage wing is closed the mixture passage wing is open, the air passage wing being of larger area and heavier

than the mixture passage wing; so that the mixture passage wing is normally open and 10 is closed more or less by suction against the air passage wing.

In testimony whereof I have signed my name to this specification.

GEORGE E. GRAY.
